DIE STRUCTURE FOR TANGENT BENDING OF CORRUGATED SHEET METAL

Theodore O. Welindt, Kankakee, Ill., assignor to A. O. Smith Corporation, Milwaukee, Wis., a corporation of New York

Filed May 6, 1957, Ser. No. 657,305

8 Claims. (Cl. 153—46)

This invention relates to a die construction for a tangent bending apparatus and more particularly to a die construction to be used for the tangent bending of corrugated sheet metal.

In the manufacture of a corrugated sheet metal heat exchanger shell for a hot air furnace, the sheet metal is initially formed with a series of deep corrugations extending the length of the sheet. The corrugated sheet is then bent longitudinally of the corrugations by a tangent bending method to a generally oval shape to form the shell.

In order to provide the required heat transfer characteristics for the shell, the corrugations are formed with a depth substantially equal to, or greater than, the pitch. During bending of deep corrugations of this type, the portion of the corrugations along the outer radius of curvature of the bend is subjected to severe tension stresses and stretching of the metal resulting in many cases in tears or splits, while the portion of the corrugations along the inner radius of curvature of the bend is subjected to compressive stresses resulting in many cases in severe wrinkling of the metal.

The present invention is directed to a die construction for use with a tangent bending apparatus which substantially eliminates the splits and wrinkling of the deeply corrugated sheet metal which occurs with conventional die structures.

According to the invention, the die construction includes an upper die member having a generally curved working face formed with a series of corrugations which complement the corrugations of the sheet to be bent.

A lower die member is adapted to cooperate with the upper die member and is supported for rocking movement with respect to the upper die member. The sheet is clamped between the die members and as the lower die member is rocked or pivoted with respect to the upper die member, the sheet is progressively bent to the curvature of the working face of the upper die member.

As the corrugated sheet to be bent is never absolutely true in dimension and generally has some camber throughout its length, the inner portion of the lower die member is planar and free of corrugations while the outer portion is provided with corrugations which complement the corrugations of the upper die member. When the sheet is clamped between the die members, the portion of the sheet in the area of the flat die surface can adjust itself to thereby insure that the end portion of the sheet will properly nest within the corrugated die members.

In order to provide a degree of overbending to compensate for rebound or spring-back in the bent portion of the metal sheet, the outer end of the corrugated portion of the lower die member is inclined upwardly at a slight angle to a horizontal plane and the curved working face of the upper die is formed to complement this inclined section.

The present invention provides a die construction for use with a tangent bending apparatus which enables deeply corrugated sheet metal to be bent in the direction

2

of the corrugations to a substantial radius of curvature without tearing or wrinkling of the metal.

Other objects and advantages will appear in the course of the following description.

The drawings furnished herewith illustrate the best mode contemplated of carrying out the invention.

In the drawings:

Figure 1 is a perspective view of a tangent bending apparatus incorporating the die construction of the invention;

Fig. 2 is a transverse section of the die assembly with the dies in the open position;

Fig. 3 is a view of the die assembly according to the plane of line 3—3 in Fig. 2 with the dies in the closed position and the metal sheet clamped therebetween;

Fig. 4 is an enlarged fragmentary transverse section of the die assembly showing the flange of the sheet contained within a pocket in the lower die;

Fig. 5 is a transverse section showing the locking brackets for clamping the upper dies in the closed position;

Fig. 6 is a top plan view of the structure shown in Fig. 5;

Fig. 7 is a fragmentary top plan view with parts broken away and showing the hydraulic cylinder employed to raise and lower the upper dies;

Fig. 8 is a rear elevation with parts broken away of the structure shown in Fig. 7;

Fig. 9 is a sectional view similar to Fig. 2, showing one end of the sheet being bent;

Fig. 10 is a perspective view of the corrugated metal sheet before bending; and

Fig. 11 is a side elevation of the completed oval-shaped bent sheet.

The drawings illustrate a conventional tangent bending machine in which a flat corrugated sheet or workpiece 1 is bent to a generally oval configuration.

The sheet 1, as shown in Fig. 10, is formed with a series of deep longitudinally extending corrugations 2, and each side edge of the sheet is provided with a flange 3 which extends the length of the sheet. The sheet 1 is adapted to be bent in a direction longitudinally of the corrugations in a series of tangential bending operations to a generally oval or elliptical shape. The ends of the sheet are then secured together to form a heat exchanger shell or the like.

The tangent bending machine comprises in general, a frame 4 which is mounted on a foundation 5 and supports a pair of lower wing dies 6 and 7. The wing dies are rockably mounted with respect to a pair of upper dies 8 and 9 having the curvature of the shell to be formed. The sheet 1 is adapted to be clamped between the upper and lower dies, and the lower dies are each rocked or pivoted upwardly around the corresponding curved upper die to progressively bend the sheet 1 to the curvature of the upper dies.

To support the lower wing dies 6 and 7, two pairs of brackets 10 are pivotally connected to upstanding side lugs 11 on frame 4 by pins 12 at the sides of the frame. The bottom surface of each pair of brackets 10 is adapted to rest on a support bar 13 which is mounted on the upper portion of the frame 4 at the sides thereof.

The brackets 10 are provided with horizontal guideways 14, and a die support plate 15 is slidably disposed within the guideways in each pair of brackets. The die support plate 15 in turn supports a bolster plate 16, and the lower dies 6 and 7 are bolted or otherwise secured to the respective bolster plates.

To rock or pivot the lower dies upwardly about the respective upper dies, the piston rod 17 of a double acting hydraulic cylinder 18 is pivotally attached to each of the brackets 10 and the lower end of each cylinder 18 is pivotally connected to the lower end portion of frame

4. Hydraulic fluid is introduced into the cylinders through lines 19 from a source, not shown.

By introducing hydraulic fluid into the lower end portion of cylinders 18, the piston rods 17 are extended, and the die support plates 15 and the lower dies 6 and 7 are thereby pivoted upwardly to a generally vertical position, as shown in Fig. 9, while retraction of the piston rods 17 will pivot the lower dies downwardly to a generally horizontal position.

To guide the die support plates 15 during rocking movement and maintain alignment of the side edges thereof, a rack 20 is secured to each side edge of each plate 15 and is adapted to mesh with a gear segment 21 which is attached to the lugs 11 on frame 4. As the die support plates 15 are rocked with respect to the frame 4, the rack 20 travels on the gear segment 21 and maintains alignment of the plates 15 and the dies 6 and 7.

The upper dies 8 and 9 are adapted to be lowered toward the lower dies and are locked in the lowered position so that the lower dies can be pivoted therearound and progressively bend the corrugated sheet 1 disposed between the dies. The upper dies 8 and 9 are carried by arms 22 and 23, respectively, and the inner end of each arm is connected to a support plate 24 at the side of the frame.

The upper dies 8 and 9 are raised and lowered by slidably mounting the support plate 24 on a column 25 which extends upwardly from the side of frame 4. To mount the support plate 24 for sliding movement on column 25, the column is provided with a pair of outwardly extending flanges or guides 26 which are slidably disposed within vertical guideways 27 formed in the support plate. The support plate is moved vertically in relation to the column by means of a hydraulic cylinder 28 which is disposed within the column 25. The upper end of cylinder 28 is secured to upper plate 29 of column 25 and the piston rod 30 of the cylinder is connected to the lower portion of the support plate. Hydraulic fluid is introduced into the ends of the cylinder 28 through lines 31 from a source, not shown.

In order to facilitate unloading of the bent sheet 1, arm 23 and the corresponding upper die 9 are adapted to be moved relative to the other arm 22 and the corresponding die 8. This is accomplished by securing the inner end of arm 23 to a bracket 32 which is slidably mounted within horizontal guideways 33 formed in the upper and lower ends of the support plate 24.

The arm 23 and die 9 is moved laterally toward and away from arm 22 and die 8 by a hydraulic cylinder 34. The outer end of cylinder 34 is secured to support plate 24 while the piston rod 35 of cylinder 34 is attached to bracket 32. Hydraulic fluid is introduced into the ends of cylinder 34 through lines 36 from a source of fluid under pressure, not shown, to retract and extend rod 35 and thereby move die 9 toward and away from die 8.

After completion of the bending operation, the corrugated sheet 1 has a generally oval shape and can be conveniently removed from the raised upper dies by moving arm 23 toward arm 22 to decrease the spacing between the upper dies. With the arms 22 and 23 in closed relation, the oval sheet can be readily slipped from the upper dies 8 and 9 over the free ends of the arms.

To assure alignment of the upper dies with the lower dies, a pair of guide bars 37 are secured to the upper end of frame 4 and are provided with notches 38 which receive arms 22 and 23 as the upper dies are lowered toward the lower dies.

To lock the upper dies 8 and 9 in the lowermost position, a pair of outer locking arms 39 are fulcrumed to bifurcated brackets 40 secured to frame 4. The upper end of each locking arm is formed with a hook 41 which is adapted to engage a hooked bracket 42 secured to the outer ends of the respective arms 22 and 23 when the upper dies are in the lowermost position.

The locking arms 39 are actuated by means of double

acting cylinders 43 which are pivotally attached to the lower end of brackets 40. Cylinders 43 carry piston rods 44 which are pivotally attached to the lower end of the L-shaped locking arms. Hydraulic fluid is introduced into the ends of cylinders 43 through lines 45 from a suitable source of fluid under pressure. By extending piston rods 44 from the cylinders 43, the locking arms 39 are pivoted inwardly to bring hooks 41 into engagement with brackets 42 and hold the outer end of the arms against movement.

In addition to locking arms 39, two pairs of inner locking brackets 46 are provided which engage the arms 22 and 23 on either side of the upper dies when the upper dies are in their lowermost position. The locking brackets 46 are pivotally connected to guide bars 37, and to this end the guide bars are provided with embossments 47 having slots 48 within which the locking brackets 46 are pivotally secured. The upper end of each bracket 46 is provided with a hook 49 which is adapted to engage the upper surface of the respective arms 22 and 23 when the brackets are in locking position.

The locking brackets 46 are connected together by a pair of links 50 which serve to actuate the brackets in unison. The connection of links 50 to brackets 46 is such that brackets 46 will move in opposite directions to simultaneously engage or withdraw from the respective arms 22 and 23.

The brackets are actuated by a hydraulic cylinder 51 and piston rod 52 of the cylinder is connected to a connecting arm 53 which is attached to one of the brackets 46. With this construction, an extension of the piston rod 52 from the cylinder 51 moves the brackets inwardly into engagement with the arms to lock the same against movement.

According to the invention, the outer end portion of the working face of each lower wing die 6 and 7 is provided with a series of deep corrugations 54 which complement the corrugations 2 of sheet 1, and the inner end portion of the working face defines a generally flat surface 55 which is in substantially the same plane as the bottom or root of the corrugations 54.

To provide a degree of overbending to compensate for spring-back of the bent sheet, the outer portion of the corrugations 54 are inclined upwardly at a slight angle to the horizontal, as indicated by 56.

The inner ends of corrugations 54 adjacent surface 55 are tapered, as indicated by 57, to prevent tearing of the sheet during clamping.

The sheet 1 to be bent is supported on the lower dies 6 and 7 with the corrugations 2 at the end portion of the sheet registering with the corrugations 56 of the dies and the corrugations at the longitudinal center portion of the sheet 1 being spaced slightly above flat surface 55.

The side flanges 3 of sheet 1 are disposed along the sides of the die 6 and are contained by the side bar flanges 58 of upper die 8, as shown in Fig. 3. However, in the case of die 7, which is intended to bend the sheet 1 to a smaller radius of curvature, the side bar flanges 58 are eliminated and the lower die 7 is provided with side bar flanges 59. The flanges 59 are formed with slots 60 to receive the flanges 3 of the sheet. As shown in Fig. 4, the flanges 3 are bottomed within the slots 60 so that pressure is applied to the flanges during the bending operation to prevent the flanges from "crawling" out of the slots.

The upper dies 8 and 9 have working faces formed with a series of corrugations 61 which complement the corrugations 54 in dies 6 and 7 and are adapted to register with corrugations 54 to clamp the sheet 1 therebetween.

The working face of each upper die includes a straight portion 62 disposed to cooperate with the flat surface 55 of the corresponding lower die and a curved end portion 63 having the desired curvature of the bend to be made and disposed to cooperate with corrugations 54 and 56 of the lower die. The working faces of dies 8 and 9 are

provided with the curvature desired in the bent sheet, and as shown in the drawings, die 9 has a lesser radius of curvature than die 8 but it is contemplated that the working faces of the dies may be of similar curvature depending on the particular article to be fabricated.

The upper extremity of the working faces of dies 8 and 9 are provided with a contour to complement the inclined corrugations 56 of the lower dies.

The inclined corrugations 56 of the lower dies and the cooperating corrugations of the upper dies, permit over-bending of the end of the sheet to compensate for spring-back in the metal sheet after bending so that the bent end portions of the sheet will have the desired predetermined curvature.

In operation of the tangent bending machine, the upper dies 8 and 9 are initially in the raised position and the corrugated sheet 1 is placed on the lower dies 6 and 7 with the flanges 3 of the sheet facing downwardly.

To position the leading edge of the sheet 1 in proper alignment on the dies, an adjustable stop rod 64, which is supported by a bracket 65 attached to die support plate 15, is disposed within one of the corrugations 56 of die 7. The end of sheet 1 engages the stop rod 64 and is thereby properly aligned on the lower dies.

The upper die 9 is then moved outwardly away from die 8 to the extended position by operation of cylinder 34, and both dies 8 and 9 are then lowered by action of cylinder 30 to clamp the sheet 1 between the upper and lower dies.

When in the clamped position, as shown in Fig. 9, the central portion of the sheet 1 bears against the flat surface 55 of the lower dies 6 and 7. The elimination of the corrugations in the inner portions of the lower dies permits lateral adjustment of the sheet in these areas, and thereby insures proper registry of the corrugations 2 of the sheet with corrugations 54 and 56 of the lower die so that the corrugations 2 may conform with the corrugations 54 and 56 of the lower die.

As the corrugations 2 are generally not perfectly straight but have some degree of camber, it is difficult to have continuous perfect registry of the corrugations 2 and a die member of substantial length. In a case such as this with imperfect registry, splits will frequently occur in the sheet during the bending operation. However, by eliminating the corrugations in the inner end portion of the dies 6 and 7, the corrugations 2 in the area of surface 55 are able to adjust their position and thereby insure the proper registry of the corrugations 2 with the corrugations 54 of the lower dies regardless of camber or other warpage of sheet 1.

With the sheet 1 clamped between the dies, one of the die support plates 15 is then pivoted upwardly by action of cylinders 18 to thereby pivot the lower die 6 upwardly around the curved working face of upper die 8 to progressively bend the sheet 1 to the curvature of the face. With this method of bending, pressure is applied progressively along the radius of curvature of the upper die to roll the metal sheet from the line of tangency.

After the first bend has been completed, the die support plate 15 is pivoted downwardly and the opposite die support plate 15 is then pivoted upwardly to progressively bend the sheet 1 around the curved working face of upper die 9.

When the second bend has been completed, the respective die support plate is pivoted downwardly and the upper dies 8 and 9 are raised to release the partially bent sheet 1. The sheet is then removed from the dies and reversed so that the opposite unbent end is inserted on the lower dies 6 and 7.

The upper dies are again lowered, clamping the sheet, and die 6 is again pivoted around upper die 8 to progressively bend the sheet to the radius of curvature of the upper die. The bending is completed by pivoting die 7 around the upper die 9 to progressively bend the remaining end of the sheet to the curvature of the upper die.

In this final bending operation, the previously bent end of the sheet is maintained in aligned with the end being bent in the final operation by a wiper guide 66 which is secured to the upper die 9. The previously bent end of the sheet is adapted to engage the guide 66 as the sheet is bent around die 8. The guide 66 serves to maintain alignment of the ends of the sheet 1, so that the corrugations 2 at the ends will be properly opposed and aligned in preparation for joining the ends together to form the completed shell.

After completion of the bending operations, the upper dies 8 and 9 are raised, carrying the bent sheet upwardly. The arm 23 and die 9 are then moved inwardly by action of cylinder 34 to decrease the spacing between the dies 8 and 9 and thereby enable the bent sheet to be slipped over the ends of the arms 22 and 23.

The present invention provides an improved die construction for a tangent bending machine which permits deeply corrugated sheet metal to be bent longitudinally of the corrugations to an extremely small radius of curvature.

Various modes of carrying out the invention are contemplated as being within the scope of the following claims particularly pointing out and distinctly claiming the subject matter which is regarded as the invention.

I claim:

1. A die construction for a tangent bending machine employed to bend a corrugated metal sheet in a direction longitudinal of the corrugations, comprising a first die member having a working face including a generally straight portion and a generally curved portion and having a series of corrugations extending substantially along the entire length of said working face to complement and receive the corrugations of said sheet, and a cooperating second die member supported for rocking movement with relation to said first die member to progressively bend the sheet clamped between said members to the curvature of the working face of said first die member, and said second die member having a working face including a generally flat surface disposed in cooperating relation with said straight portion of the working face of said first die member and a corrugated surface disposed outwardly of said flat surface and in cooperating relation with the curved portion of said working face of the first die member.

2. A die construction for a tangent bending machine employed to bend a corrugated metal sheet in a direction longitudinal of the corrugations, comprising an upper die member having a generally curved working face and a series of corrugations extending transversely of the working face, and a cooperating lower die member supported for rocking movement with relation to said upper die to progressively bend the sheet between said members to the curvature of the working face of the upper die member, said lower die member having a working face including a generally planar inner section disposed at the inner end of said lower die member and having an outer section formed with a series of corrugations complementing the corrugations of the working face of the upper die member, the outer end portion of said outer section being disposed at an inclined angle to the remaining portion of the outer section.

3. A die construction for a tangent bending machine employed to bend a corrugated metal sheet in a direction longitudinal of the corrugations, comprising a first die member having a working face including a central section and a generally curved outer section, said first die member having a series of corrugations extending substantially along the entire length of said working face to complement and receive the corrugations of said sheet, and a cooperating second die member supported for rocking movement with relation to said first die member to progressively bend the sheet clamped between said members to the curvature of the curved outer section of the working face of said first die member, said

second die member having a working face including a generally flat surface disposed in cooperating relation with said central section and an outer corrugated portion disposed in cooperating relation with the curved section of the working face of said first die member, and means associated with the working face of each of said die members for overbending the sheet beyond the desired radius of curvature to compensate for spring-back in the metal sheet.

4. A die construction for a tangent bending machine employed to bend a corrugated metal sheet in a direction longitudinal of the corrugations, comprising an upper die member having a generally curved working face and a series of corrugations extending transversely of the working face, a cooperating lower die member supported for rocking movement with relation to said upper die member to progressively bend the sheet between said members to the curvature of the working face of the upper die member, said lower die member having a working face formed with a series of corrugations complementary to the corrugations of said working face of the upper die member, and means associated with the inner portion of the working face of the lower die member for effecting lateral adjustment of the metal sheet as the same is clamped between the die members and thereby eliminating tearing and splitting of the sheet during the bending operation.

5. A die construction for a tangent bending machine employed to bend a corrugated metal sheet in a direction longitudinal of the corrugations with said corrugated metal sheet having a side flange extending along a side edge thereof, comprising an upper die member having a working face including a straight portion and a generally curved portion and having a series of corrugations extending transversely of the working face, and a cooperating lower die member supported for rocking movement with relation to said upper die to progressively bend the sheet between said members to the curvature of the working face of the upper die member, said lower die member having a working face including a generally flat surface disposed in cooperating relation with said straight portion of the working face of said upper die and having an outer portion disposed to cooperate with the curved portion of the working face of the upper die and formed with a series of corrugations complementary to the corrugations of the working face of the upper die member, and means associated with one of said die members for exerting a force against the edge of the flange of the sheet during the bending operation to prevent movement of the flange during the bending.

6. A die construction for a tangent bending machine employed to bend a corrugated metal sheet in a direction longitudinal of the corrugations with said corrugated metal sheet having a side flange extending along a side edge thereof, comprising an upper die member having a working face including a straight portion and a generally curved portion and having a series of corrugations extending transversely of the working face, and a cooperating lower die member supported for rocking movement with relation to said upper die to progressively bend the sheet between said members to the curvature of the working face of the upper die member, said lower die member having a working face including a generally flat surface disposed in cooperating relation with said straight portion of the working face of said upper die and having an outer portion disposed to cooperate with the curved portion of the working face of the upper die and formed with a series of corrugations complementing the corrugations of said working face

of the upper die member and having a slot formed in the side edge portion thereof and disposed to receive the flange of said sheet, said slot having a depth sufficient for the edge of the flange to bear against the bottom of said slot during the bending operation to thereby confine the flange during bending.

7. A die construction for tangent bending of corrugated metal sheet in a direction longitudinal of the corrugations to form a generally oval-shaped article, comprising a frame, a pair of separate spaced first die members carried by the frame with each first die member having a generally curved working face and having a series of corrugations extending transversely of the working face, a pair of second die members supported by the frame for rocking movement with relation to the respective first die members to progressively bend the sheet to the curvature of the working face of the first die members, said second die members having working faces provided with a series of corrugations complementing the corrugations of the working face of the respective first die members, guide means associated with at least one of said first die members for maintaining alignment of the corrugations of the portion of the sheet projecting outwardly of the die members with the corrugations of the portion of the sheet disposed between the die members, and means for moving the first die members relative to each other to decrease the spacing therebetween after the bending operation and permit removal of the bent sheet from the first die members.

8. A die construction for a tangent bending machine employed to bend a corrugated metal sheet in a direction longitudinal of the corrugations, comprising an upper die member having a generally curved working surface and a series of corrugations disposed on the working surface, a cooperating lower die member supported for rocking movement with relation to the upper die to progressively bend the sheet between said die members to the curvature of the working face of the upper die member, said lower die member having a working face formed with a series of corrugations complementary to the corrugations of said working face of the upper die member and having the outer portion of said working face disposed at an inclined angle with respect to the inner portion of said working face, means associated with the working face of the upper die member to receive said inclined portion of the lower die member to effect overbending of the end portion of the sheet to accommodate springback of the same, and means associated with the inner portion of the working face of the lower die member for effecting lateral adjustment of the metal sheet as the same is clamped between the die members and thereby eliminating tearing and splitting of the sheet during the bending operation.
